UNITED STATES PATENT OFFICE.

RICHARD R. HALSTEAD, OF BEACH, NORTH DAKOTA.

ANTISLIPPING DEVICE.

Application filed April 4, 1927. Serial No. 180,905.

The present invention relates to improvements in anti-slipping devices, for association with shoes and has for its principal object to provide a simple and efficient device which is attached to the heel of the shoe, the same including a plurality of ground engaging calks which protrude below the bottom surface of the heel, whereby the wearer will not slip on icy or muddy surfaces, while walking over the same.

Another important object of the invention is to provide an anti-slipping device of the above mentioned character, which includes a means for simultaneously actuating all of the ground engaging calks for moving the same to an operative or inoperative position.

A further object is to provide an anti-slipping device of the above mentioned character, which may be associated with a shoe heel in such a manner as not to present an unsightly appearance.

A still further object is to provide an anti-slipping of the above mentioned character, which is simple in construction, strong and durable, and further well adapted to the purpose for which it is designed.

Other objects and advantages of the invention will become apparent during the course of the following detailed description, taken in connection with the accompanying drawings, forming a part of this application.

In the drawing:

Figure 1 is a bottom plan view of the anti-slipping device embodying my invention.

Figure 2 is a longitudinal sectional view, taken approximately on the line 2-2 of Figure 1, for more clearly disclosing the construction of the worm shaft.

Figure 3 is a sectional view, taken approximately on the line 3-3 of Figure 1, looking in the direction of the arrows.

Figure 4 is a detail perspective view of one of the ground engaging calks.

Figure 5 is an enlarged vertical sectional view, through the calk showing the hardened center, and

Figure 6 is a detail perspective view of the sleeve and the worm wheel carried by the upper end thereof.

In the drawing, wherein for the purpose of illustration is shown the preferred embodiment of my invention, the numeral 1 designates generally my improved anti-slipping device, the same comprising a sub-

stantially rectangular shaped block or casing 2 and extending longitudinally therein adjacent one side thereof is the rotatable shaft 3, the same being formed at spaced intervals with the worms 4. In the present instance, three of such worms are disclosed, although it is to be understood that I do not wish to limit myself to the particular number which may be provided. The purpose of these worms will hereinafter be more fully described.

A head 5 is formed on one end of this shaft 3 and engages one end of the casing or block 2. The other end of the shaft carries thereon a suitable thumb engaging member 6, whereby the shaft may be actuated.

Also forming a part of the present invention are the depending relatively short housings 7, the upper end of each housing being formed with an attaching flange 8, which is adapted to be secured to the bottom of the block or casing 2, by any appropriate fastening means, such as are shown at 9. Each housing is provided with an internally threaded bore, and arranged for vertical movement within each housing is the externally threaded calk 10. The lower end of each calk is pointed as at 11, to provide a sharp ground engaging element, and as is more clearly shown in Figure 5, the center of each calk is hardened, and the hardened portion is indicated by the numeral 12.

By constructing the ground engaging calk with a center core of nickel chrome steel and the outer portion of the calk being of a softer steel, this element or member will not be apt to break and furthermore the point 11 will wear sharp, instead of dull.

The calk 10 is formed at its upper end with an elongated shank 13, and the same is substantially rectangular in cross section, for a purpose to be presently apparent.

Removably fitted on each of the rectangular shaped shanks 13 is the relatively short sleeve 14, the bore thereof being also rectangular for cooperation with the rectangular shaped shank. A worm wheel 15 is formed on the upper end portion of this sleeve and as is clearly shown in Figure 3, the block or casing 2 is provided with a pocket for accommodating the sleeve and the worm wheel associated therewith.

The worm wheels will be in engagement with the respective worms 4 arranged on the rotatable shaft 3, so that all of the sleeves will be rotated simultaneously.

In operation, the pointed ends of the calks normally are held out of engagement with the ground so that the pointed ends of the calk will be disposed above the bottom face of the heel in which the anti-slipping device is embedded or otherwise arranged. In order to prevent any possibility of a person slipping on an icy or muddy surface, it is only necessary to turn the thumb engaging member 6, in one direction, so that the shaft 3 is rotated, and as this shaft is rotated, the worms 4 will cooperate with the worm wheels 15 to rotate the sleeves 14. As the bores of the sleeves are rectangular and receive the rectangular shanks 13 of the calks 10, the latter will be threaded outwardly of the internally threaded housings 11, so that the pointed lower ends of the calks will protrude beyond the body face of the heel and will engage the surface so that the wearer of the device may travel over any icy or muddy surface without any danger of slipping or falling.

The simplicity in which my device is constructed enables the parts to be readily and easily assembled and furthermore all of the calks will be operated simultaneously so that one calk will not protrude a greater distance than the other calks.

The anti-slipping device may be employed on rubbers and overshoes as well as the ordinary type of shoes.

While I have shown the preferred embodiment

ment of my invention, it is to be understood that various changes in the size, shape and arrangement of parts may be resorted to without departing from the spirit of the invention or the scope of the appended claim.

What I claim is:

An anti-slipping device comprising a casing adapted to be embedded in a shoe heel, a rotatable shaft extending through the casing, a series of internally threaded housings adapted to be embedded in a shoe heel, an attaching flange formed on the upper portion of each housing for attachment to the bottom of the casing, an externally threaded calk arranged within each internally threaded housing, the lower end of each calk being pointed for engagement with the ground, a rectangular shank formed on the upper end of each calk and extending into the casing, a plurality of sleeves arranged in the casing directly above the respective housings, the bore of each sleeve being rectangular for receiving the rectangular shank of the respective calk, the shank being slidable in the sleeve, a worm wheel formed on the upper portion of each sleeve, said shaft being formed with a series of worms for cooperation with the respective worm wheels whereby the calks may be raised or lowered when the shaft is actuated.

In testimony whereof I affix my signature.

RICHARD R. HALSTEAD.
